HOUSING FOR A DICTATING MACHINE

William J. O'Neil, New York, N. Y., assignor to Dictaphone Corporation, Bridgeport, Conn., a corporation of New York

Application December 21, 1953, Serial No. 28,141

Term of patent 14 years

(Cl. 26—11)

Fig. 1.

Fig. 2.

Fig. 3.

Fig. 4.

Fig. 5.

Fig. 6.

Figure 1 is a perspective view of the front and one side of a housing for a dictating machine showing my new design;

Figure 2 is a perspective view of the rear and the opposite side thereof;

Figure 3 is a side elevation of the housing;

Figure 4 is a front elevation;

Figure 5 is a rear elevation; and

Figure 6 is another side elevation.

The dominant features of my design reside in the portions shown in the full lines in the drawings.

The design is characterized by the applied ornamental strip which runs as a raised ribbon horizontally along the side walls of the housing and substantially completely therearound; by the overall streamline effect of the top

of the housing being smoothly curved into the side walls and sloping downwardly toward the rear; and also by the shape and size of the front opening which is substantially less than one-half of the width of the front of the housing.

I claim:

The ornamental design for a housing for a dictating machine, substantially as shown and described.
